UNITED STATES PATENT OFFICE.

CHARLES D. LANNING, OF BOSTON, MASSACHUSETTS.

WARP STOP MECHANISM FOR LOOMS.

976,377.

Specification of Letters Patent. Patented Nov. 22, 1910.

Continuation of application filed November 17, 1905, Serial No. 287,866. This application filed August 4, 1908. Serial No. 446,857.

To all whom it may concern:

Be it known that I, CHARLES D. LANNING, a citizen of the United States of America, residing at Boston, in the county of Suffolk and Commonwealth of Massachusetts, have invented certain Improvements Appertaining to Warp Stop Mechanism for Looms, of which the following is a specification, this application being a continuation of application 5 cant's prior application Serial No. 287,866, filed Nov. 17, 1905.

A portion of the usual devices employed in connection with warp-stop mechanism in looms are bars or rods extending transversely thereof, some of which support the warp-threads, and also serve as lease-rods, and others engage and control the vertical movement of the drop-bars, which are hung upon the threads. When changing warps in a loom or renewing broken or damaged drop-bars, it becomes necessary to remove all or some of these rods; and so far as I am aware, to accomplish this it has heretofore been necessary to remove a part of the end frame 20 of the loom, which freed all of the rods simultaneously and rendered it difficult to support and manipulate them.

My invention consists in means upon the frame for supporting these rods and on which each one may be readily placed or removed separately, without disturbing in any manner the others, or the loom-frame, and also in devices by which the rods may be readily secured or locked in place upon 35 their supports and as easily released for the purpose of removal. One form of means for this purpose is illustrated in the drawings, wherein—

Figure 1 is a perspective view of a portion 40 of a loom-frame, showing the warp-supporting rods and drop-bar controlling rods in proper position, with a small portion of the warp-threads and drop-bars hung thereon, and the devices for securing the several bars 45 in their supports. The middle portion of the bars and frame is broken away; Fig. 2 is a detail elevation of one end of the frame viewed from within, showing the device in full lines for securing the warp-rods in their 50 supports, and in broken lines the device for securing the drop-bar rods; Fig. 3 is a side elevation of the same parts as are contained in Fig. 2; Fig. 4 shows a securing device for the drop bar guide rods, detached from the 55 bracket, and with a slot at one side of the

hole for the guide rod, so that the securing device may be swung to one side upon a pintle attachment at its upper end; Fig. 5 shows partly in end elevation and partly in section, a loom frame having my invention 60 applied thereto; Fig. 6 is a detail in enlarged vertical section upon the line 6—6, Fig. 5, of a portion of a loom frame having my invention applied thereto, the drop-bars being omitted; Fig. 7 shows in end elevation 65 means for supporting movable lease rods at one end of the loom frame; Fig. 8 is a side elevation of the construction shown in Fig. 7; Fig. 9 is a horizontal section upon the line 9—9, Fig. 7; Fig. 10 is an end elevation, viewed from within, of the end of the loom opposite that shown in Fig. 7 and representing my invention as there applied to the lease rods; Fig. 11 is a side elevation of 70 the construction shown in Fig. 10; Fig. 12 is 75 a horizontal section upon the line 12—12 of Fig. 10; Figs. 13 and 14 are views in end and side elevation respectively of a modified form of means for supporting movable lease rods at one end of the loom; and Figs. 15 80 and 16 are similar views of the opposite end of the loom, and representing my invention as there applied to the lease rods.

In the drawings, the improvements are illustrated as applied at one end only of the 85 rods, and this will be sufficient for practical purposes; but it will be readily understood that these devices may be applied at both ends of the rods if found desirable.

Referring to the drawings and first to the 90 construction shown in Figs. 1 to 4 thereof, the end parts of the loom which are partially represented at 1, 1', suitably receive drop bar controlling or tie rods 2, 2, passing 95 through suitable slots 3 in the drop bars 4 supported upon the warp threads 5 which are suitably sustained by the warp supporting or lease rods 6, 6. Preferably said lease rods are tubular to secure lightness with the desired size, and at one end are fitted upon 100 suitable and preferably tapering studs 7, 7 suitably secured in the end portion 1' of the loom. Suitably positioned beneath the drop bars and insulated at its ends from the loom frame is a contact bar 8 having connected thereto a circuit wire 9 (see Figs. 1 and 6) which is suitably connected to a battery 10 or other source of electrical energy (see Fig. 5), with which is connected by wire 11 a 105 magnet 12 preferably stationarily mounted 110

upon the loom frame, and adapted when energized to attract the armature 13, and thereby through link 14 to position the bunter 15 in the path of the lay. Metallic 5 guide bars 15' (see Fig. 1) serve as the opposite terminal for the drop bars.

While the end part 1, 1' of the loom may be of any suitable construction, preferably, for convenience of application and adjustment, I attach to the upper part thereof brackets 16, 16', and upon the inner face of the bracket 16' form open, preferably U-shaped pockets, supports or partial bearings 17, 17, represented in full and dotted lines 15 in Fig. 2, and into which an end of each of the lease rods 6 may be placed after the opposite ends have been slipped over the studs 7. While any suitable means may be provided to secure the lease rods in position, 20 I preferably provide (see Figs. 1, 2 and 3) a locking lever 18 fulcrumed at 19 upon a projecting part 20 of the bracket 16'. While separate levers or other locking or securing means may be provided for the lease rods, 25 preferably the lower end of the lever 18 is suitably widened to engage both lease rods, and is provided with sockets or partial bearings 20' at the lease rod contacting portions thereof to engage such rods.

30 The drop bar controlling rods may be conveniently supported and held in place in the brackets 16, 16' by drilling holes 21 through the bracket 16' and sockets 22 partly through the bracket 16, the rods being inserted through the holes 21 and then threaded through the drop bars into the sockets 22. Any suitable means may be employed to retain the rods in position. In Figs. 1 and 3 is shown a retaining latch or 35 member 23 adapted to slide vertically upon the outer face of the bracket 16' and provided with an operating handle 24. The latch is slotted as represented at 25 to receive a pin or bolt 26 extending from the bracket 16' 40 and provided with nut 27 upon its outer end. A projecting portion of the bracket 16' may extend through the slot 25 to guide the movement of the latch. If desired the latch may be fastened in position by making the 45 projection on the bracket slightly greater than the thickness of the latch and tightening the nut 27 upon the pin. As shown in Fig. 4, the latch may be constructed to swing upon a pivot, it being provided with a trans- 50 verse slot 29 to permit the passage of the pin or bolt 26. By reason of the pivotal support of the latch or locking device, it may be swung into or out of locking relation to the rods 2, 2, without detachment 55 from the frame, and it will be held by gravity in its locking position. Similarly, the locking lever 18 is held by gravity in locking position.

In Figs. 7 to 12 inclusive, I have shown a 60 modified form of my invention wherein the

lease rods 30—30 are so mounted upon the loom frame as to permit movement thereof freely up and down in conformity with any leveling requirements of the warp, and also preferably toward the fell of the cloth, 70 while at the same time supporting the warp threads against the additional weight of the drop bars. The several parts are so supported as to permit the described movements of the lease rods independently of the 75 means for guiding the movement of an indicating drop bar and also of the means coöperating with said indicating drop bar to stop the loom. The lease rods may be mounted in any suitable manner, for either simultaneous or independent movement, to accomplish these results.

As shown in Figs. 7 and 9, the lease rods 30, 30 are preferably mounted at one end, as for example at the right hand end viewing 85 Fig. 1, upon an oscillatory member 31 loosely mounted upon a bolt 32 carried by a block 33 attached to or formed upon one face of the oscillatory member 31, and mounted for lateral, sliding movement in an elongated slot 34 in the bracket 35, thereby permitting movement of the oscillatory member toward the fell of the cloth. Preferably a spring 36 is interposed between the block 33 and the bracket 35 to cushion such movement. The oscillatory member 31 is provided with preferably tapering studs 37 to receive the ends of the lease rods. At the opposite end, and as shown in Figs. 10 to 12, the lease rods are mounted in partial 100 bearings 38 formed upon opposite portions of an oscillatory member 31, preferably similarly supported. While any suitable means may be provided to secure the lease rods in position in said member, herein I have represented a locking lever 39 pivoted at 40 upon an extension 41 from the oscillatory member 31, said lever being preferably forked or widened at its lower end and provided with partial bearings 42 to engage the 105 lease rods and hold them firmly in position. Although separate locking levers may be provided for the lease rods, preferably a single lever is employed as in this form of the invention the lease rods have a simultaneous or dependent movement. My invention may, however, be utilized in connection with leasing members supported independently of each other individually to conform 110 to the leveling requirements of the warp.

In Figs. 13 to 16, I have shown one form of means effective for the purpose. Therein (Figs. 13 and 14) the lease rods 43 are preferably supported at one end upon studs 44 projecting from rocking arms 45 loosely mounted upon bolts 46 projecting from the loom frame, springs 47 being provided, which when under tension normally support the weight of the lease rods, their supporting arms and coöperating parts, so that said 120 125 130

arms are normally free of the stops 48, 48, and are free to move in accordance with the leveling requirements of the warp. At the opposite end, and as shown in Figs. 15 and 5 16, the arms 45 are provided with partial bearings to receive the ends of the lease rods 43 and are also provided with extensions 49 whereon are pivoted at 50 locking levers 51, whose lower ends are provided with partial 10 bearings 52 to engage the lease rods and hold them in place. Any other suitable locking or securing means may be employed.

It is apparent that locking or securing means may be provided for both ends of the 15 lease rods shown in Figs. 7 to 16.

While this invention is of general application, it is particularly applicable to those constructions of looms wherein the warp supporting bars are employed as lease rods, 20 as for instance in the Coldwell & Gildard Patent No. 690,636, January 7, 1902, wherein in the warp threads pass under as well as over the rods, so that in the operation of the loom there is a tendency to lift the rods as 25 well as to pull them forward when the lay beats up the weft, and wherein the tie rods or drop-bar controlling rods have an upward strain put upon them by the drop-bars, due to the vertical vibration of the warp 30 threads upon which they are supported.

Having thus described one type or embodiment of my invention, I desire it to be understood that although specific terms are employed, they are used in a generic and descriptive sense and not for purposes of limitation, the scope of the invention being set forth in the following claims.

Claims.

1. A loom having in combination a frame, 40 transverse rods, open-bearing rod supporting devices upon the loom frame upon which the ends of said rods may be readily placed and removed without movement of said supporting devices, and rod holding means normally mounted for rod-releasing movement and structurally separate from said supporting devices but coöperating therewith to sustain said rods in position, and permitting, by reason of said normal mounting, the 45 ready insertion and removal of said rods with respect to said supporting devices without disassembling of said holding means.

2. A loom having in combination a frame, transverse rods, open-bearing rod supporting devices supported by the loom frame, and upon which the ends of said rods may be readily placed and removed without movement of said supporting devices, and rod holding means structurally separate 55 from said supporting devices and normally mounted for rod-releasing movement relative to the loom frame and coöperating with said supporting devices to sustain said rods in position and permitting, by reason of said 60 normal mounting for movement relative to

the loom frame, the ready insertion and removal of said rods with respect to said supporting devices without disassembling movement of said holding means.

3. A loom having in combination a frame, 70 transverse rods, open-bearing rod supporting devices supported by the loom frame and upon which the ends of said rods may be readily placed and removed without movement of said supporting devices, and 75 rod holding means structurally separate from said supporting devices and pivotally mounted for movement relative to the loom frame for rod-releasing normal movement and coöperating with said supporting devices to sustain the said rods in position, said rod holding means when swung upon their pivotal supports permitting the ready application of said rods to and their removal from said supporting devices. 80

4. A loom having in combination a frame, transverse rods, opposite brackets supported upon the loom frame, one at least of said brackets being provided with open-bearing 90 rod supporting devices upon which the ends of said rods may be readily placed and removed without movement of said supporting devices, and rod holding means normally mounted for rod-releasing movement upon one at least of said brackets, and coöperating 95 with said supporting devices to sustain said rods in position, and permitting by reason of said normal mounting the ready insertion and removal of said rods with respect to said supporting devices without disassembling 100 movement of said holding devices.

5. A loom having in combination a frame, transverse rods, open-bearing rod supporting devices supported by the loom frame, and to which the ends of said rods may be 105 readily applied and removed without movement of said supporting devices, and rod holding means structurally separate from said supporting devices and normally mounted for rod-releasing movement relative to the loom frame and coöperating with said supporting devices to sustain said rods in 110 position and permitting, by reason of their normal mounting, the ready application and removal of said rods with respect 115 to said supporting devices without disassembling movement of said holding means.

6. A loom having in combination a frame, transverse rods, rod supporting devices upon the loom frame constituting partial bearings for said rods and into which partial bearings the ends of said rods may be readily placed and removed without movement of said supporting devices, and rod holding means structurally separate from said partial bearings and normally movable with respect thereto for rod-releasing movement and coöperating therewith to sustain said rods in position in said partial bearings and permitting, by reason of their movable 120

125

130

- mounting, the ready insertion and removal of said rods with respect to said partial bearings without disassembling movement of said holding means.
- 5 7. A loom having in combination a frame, hollow, transverse rods, projections supported by one side of the loom frame and adapted to enter and hold said rods at one end, open-bearing rod supporting devices 40
10 supported by the opposite side of the loom frame and upon which the opposite ends of said rods may be readily placed and removed without movement of said supporting devices, and rod holding means normally 45
15 mounted for rod-releasing movement at the same side of the loom frame as said supporting devices and structurally separate from the latter but coöperating therewith to sustain said rods in position and permitting, by
20 reason of said movable mounting, the ready insertion and removal of said rods with respect to said supporting devices without disassembling movement of said holding means.
25 8. A loom having in combination a frame, transverse lease rods, open-bearing rod supporting devices for said lease rods movably mounted upon the loom frame to permit movement of said lease rods to conform to
30 the leveling requirements of the warp, the ends of said rods being readily applied to and removable from said supporting devices without necessary movement of the latter, and holding means structurally separate
35 from said supporting devices but coöperating therewith to sustain said rods in position 60
- and movably mounted to conform in unison with said supporting devices to said leveling requirements of the warp and normally mounted for rod-releasing movement relative to said supporting devices, thereby to permit the ready insertion and removal of said rods with respect to said supporting devices without disassembling movement of said holding means. 65
9. A loom having in combination a frame, open-bearing rod supporting devices movably mounted upon the loom frame, a lease rod mounted upon said supporting devices and movable therewith in response to the leveling requirements of the warp, and lease rod holding means structurally separate from said supporting devices but coöperating therewith to sustain said rod in position and movable in unison with said devices to permit movement of the lease rod in conformity to the leveling requirements of the warp, said holding means being normally mounted for rod-releasing movement relative to said holding means, thereby to permit the ready insertion and removal of said rods with respect to the supporting devices without disassembling movement of said holding means. 70

In testimony whereof, I have signed my name to this specification, in the presence of two subscribing witnesses.

CHARLES D. LANNING.
